CLAIM

We claim the ornamental design for a printer, as shown and described.

DESCRIPTION

FIG. 1 is a front perspective view of a printer showing our new design;

FIG. 2 is a front perspective view thereof;

FIG. 3 is a rear elevational thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is another front perspective view of the printer with a display screen in an alternate position.

The broken lines in the drawings are environmental and are for illustrative purposes only, forming no part of the claimed design.
